Primary Examiner — Jeffrey D Asch*Assistant Examiner* — Caitlin A Laverty(74) *Attorney, Agent, or Firm* — Dority & Manning, P.A.(57) **CLAIM**

The ornamental design for a flared foldable utility enclosure, as shown and described.

DESCRIPTION

FIG. 1 is a top, front, right perspective view of a flared foldable utility enclosure showing our new design;

FIG. 2 is a front elevational view thereof, which is identical to a rear elevational view;

FIG. 3 is a right side elevational view thereof, which is identical to a left side elevational view;

FIG. 4 is a top plan view thereof;

FIG. 5 is a bottom plan view thereof;

FIG. 6 is a perspective view of the flared foldable utility enclosure in a folded state;

FIG. 7 is a front elevational view thereof, which is identical to a rear elevational view;

FIG. 8 is a right end elevational view thereof, which is identical to a left end elevational view;

FIG. 9 is a top plan view thereof; and,

FIG. 10 is a bottom plan view thereof.
